DESIGN FOR A BOX

Robert H. Clark, Los Angeles, Calif.

Application December 1, 1944, Serial No. 116,647

Term of patent 14 years

(Cl. D58—12)

To all whom it may concern:

Be it known that I, Robert H. Clark, a citizen of the United States, residing in the city of Los Angeles, county of Los Angeles, and State of California, have invented a new, original, and ornamental Design for a Box, of which the following is a specification, reference being had to the accompanying drawing, forming a part thereof.

Fig. 1 is a plan view of a box showing my new design; Fig. 2 is a side elevation of the box taken from one side thereof; Fig. 3 is a side elevation of the box taken from the other side thereof; Fig. 4 is an end elevation of the box taken from one end thereof, and Fig. 5 is an end elevation of the box taken from the other end thereof.

I claim:

The ornamental design for a box, as shown.

ROBERT H. CLARK.
